UNITED STATES PATENT OFFICE

113,278

DESIGN FOR A COAL RANGE

Ambrose R. Pierce, St. Louis, Mo., assignor to
American Stove Company, St. Louis, Mo., a cor-
poration of New Jersey

Application September 8, 1938, Serial No. 79,793

Term of patent 14 years

To all whom it may concern:

Be it known that I, Ambrose R. Pierce, a citizen of the United States, residing in the city of St. Louis and State of Missouri, have invented a new, original, and ornamental Design for Coal Ranges, of which the following is a specification, reference being had therein to the accompanying drawing.

In the accompanying drawing,

Figure 1 is a perspective view of a coal range embodying my new design with the front doors in closed position, and

Figure 2 is a perspective view thereof on a slightly enlarged scale, showing said front doors in open position.

The ends of the range are like the end shown in Figure 1.

This application is a continuation-in-part of my application Serial No. 72,705, filed November 8, 1937.

The dominant features of the design consist of a coal range having the interior contour or pattern of the parts when the range is open as shown in Fig. 2.

I claim:

The ornamental design for a coal range, as shown and described.

AMBROSE R. PIERCE.
